UNITED STATES PATENT OFFICE.

JAMES MATHIE, OF NORTH ALTON, ILLINOIS.

HITCH-CLAMP.

SPECIFICATION forming part of Letters Patent No. 244,020, dated July 5, 1881.

Application filed May 3, 1881. (No model.)

To all whom it may concern:

Be it known that I, JAMES MATHIE, of North Alton, county of Madison, and State of Illinois, have invented a new and useful Improvement 5 in Hitch-Clamps, of which the following is a clear, full, and exact description, reference being had to the accompanying drawings, making a part of this specification, in which—

Figure 1 is a perspective view of a hitch-clamp with my improvements attached. Fig. 10 2 is a plan view of the same. Fig. 3 is a vertical cross-section through *x x*. Fig. 4 is a longitudinal section through *y y*.

My invention relates to clamps for holding 15 reins of bridles and driving-lines; and it consists in the combination of devices hereinafter described and claimed.

To enable others skilled in the art to make 20 and use my invention, I will proceed to describe the exact manner in which I have carried it out.

In the drawings, A represents the main block or frame of the device, slotted, as shown at *a a*, Fig. 4, to receive the cams B, which are pivoted 25 at *b* within the slots *a*. Mounted on the outer faces of these cams, and rigidly attached thereto, are the vertical clamping-faces C, between which the lines or reins are clamped and held. Against each cam bears a spring, D, by which 30 the cam-faces are forced together, as shown in Fig. 2. It is evident from this description that if the cams B be forced back against the springs D their faces and the clamping-faces C will separate or open the space between them sufficiently for the reception of a pair of driving-lines 35 or bridle-reins, and on being released will close

tightly on the lines or reins and hold them securely until released by again forcing back the cams against the springs.

In order to guard against the possibility of 40 the lines working upward and out from between the cams, a button, *d*, may be used, so as to cross the space between the clamp-blocks.

To the central and lower portion of the main block A, I secure the small screw-clamp E, as 45 shown in Fig. 3, by which means my improved hitching device becomes portable and detachable, and can be conveniently and quickly attached and detached wherever and whenever desired.

To guard against the possibility of damage 50 by the thumb-screw *e* to the splash-board of a vehicle, the washer *e'* is loosely swiveled on the inner end of the thumb-screw, and receives the thrust of the screw when the hitch-clamp is secured in position.

I am aware that it is not new to use the cam in the construction of hitch-clamps, nor do I claim such, broadly, as my invention; but,

Having thus described my invention, what 60 I claim as new, and desire to secure by Letters Patent, is—

The improved hitch-clamp, constructed as described, and consisting of the slotted block A, cams B, provided with the springs D and 65 vertical clamping-faces, and the screw-clamp E, all constructed to operate substantially as and for the purpose set forth.

JAMES MATHIE.
